GRINDING MACHINERY

Sol Einstein, Clement Booth, and Frederick S. Haas, Cincinnati, Ohio, assignors, by mesne assignments, to The Heald Machine Company, Worcester, Mass., a corporation of Massachusetts

Application June 26, 1929, Serial No. 373,791

28 Claims. (Cl. 51—50)

This invention relates to improvements in grinding machinery and particularly to mechanism adapted for the automatic performance of a grinding cycle.

- 5 One of the objects of the present invention is the provision of an automatic grinding machine which will automatically engage and support the work piece, bring the work piece and grinding member into operative relation one to the other, 10 perform the desired grinding operation, disassociate the parts and eject the finished work piece, the latter being automatically replaced in the work supporting member by an unground work piece.
- 15 A further object of the invention is the provision of an improved machine particularly adapted for generation of an inner cylindrical or like surface by performance of what is known as internal grinding in which the several functionings of the machine are automatically controlled to effect continuous cyclic operation on a series 20 of similar work pieces for the reduction of each successive work piece to the same predetermined size.
- 25 A further object of the invention is the provision of novel electrical hydraulic control mechanisms for sequentially effecting a predetermined series of relative movements of the work holder and cutting tool of a grinding or other metal 30 working machine.

- An additional object of the invention is the provision of an improved automatic internal or like grinding machine in which the relative position of the several essential elements thereof 35 and their degrees of relative movement may be adjusted and varied as desired but in which the operative functionings thereof in any position of adjustment may be either automatically or manually effected.
- 40 An additional object of the invention is the provision of an improved automatic machine for sequential operation on a series of work pieces which shall be automatically controlled for effecting the individual grinding cycles and additionally automatically controlled to secure accurate duplication of grinding action on all pieces 45 of the series.

- Other objects and advantages of the present invention should be readily apparent by reference to the following specification considered in conjunction with the appended drawings forming a part thereof, and it will be understood that any modification in the specific structural details or combination and arrangement of parts hereinafter disclosed may be made within the scope

of the appended claims without departing from or exceeding the spirit of the invention.

In the drawings there has been illustrated one embodiment of the generic principles of the present invention in which;

Figure 1 is a front elevation thereof.

Figure 2 is a top plan view.

Figure 3 is a transverse section illustrating the grinding wheel in operative engagement with the work as on the line 3—3 of Figure 1.

Figure 4 is a longitudinal section through the work head as on line 4—4 of Figure 2.

Figure 5 is a transverse section through the work head carriage and drive mechanism as on the line 5—5 of Figure 2.

Figure 6 is a similar transverse section through the table and bed as on line 6—6 of Figure 1 illustrating the work feed mechanism.

Figure 7 is a section through the automatic feed compensating mechanism on line 7—7 of Figure 6.

Figure 8 is a fragmentary vertical sectional view on the line 8—8 of Figure 6.

Figure 9 is a sectional view at right angles to Figure 8 on the line 9—9 of said figure.

Figure 10 is a view in elevation of the control box with the cover plate removed.

Figure 11 is a vertical section through said control mechanism on the line 11—11 of Figure 10.

Figure 12 is a section through the table actuating and control valve mechanism on line 12—12 of Figure 11.

Figure 13 is a section through the coupled feed and ejector control valve mechanisms as on line 13—13 of Figure 11.

Figure 14 is a section through one of the switch members as shown in Figure 10.

Figure 15 is a similar section through one of the resiliently actuated make and break switch members.

Figure 16 is a section through the automatic coolant control valve.

Figure 17 is a fragmentary section on line 17—17 of Figure 1 illustrating the feed arm actuator.

Figure 18 is an enlarged fragmentary view of the cam control for axial movement of the feed arm.

Figure 19 is a fragmentary section as on line 19—19 of Figure 3, showing one of the spring actuated work retaining members carried by the arm.

Figure 20 is a similar section as on line 20—20.

Figure 21 is a section on line 21—21 of Figure 11.

5 Figure 22 is a diagrammatic view illustrating the complete hydro-electric control and actuating mechanisms for performance of the sequential automatic grinding cycles, and

10 Figure 23 is a perspective phantom view particularly illustrating the location and arrangement of the several hydraulically actuated units for effecting movement of the parts of the machine.

15 The general construction and operation of our improved machine will be best understood by reference to Figures 1 to 4 inclusive of the drawings.

20 From this it will be noted that in the embodiment here chosen for purposes of illustration it comprises primarily a main bed 30 having ways 31 at one side and a lower set of ways 32 at the opposite side. Mounted on the ways 31 is the slide or carriage 33 bearing a drive motor 34, a jack shaft 35 for transmitting power to the 25 grinding wheel spindle 36 provided with a small diameter or internal grinding wheel 37.

25 This spindle is mounted on carriage 33 for rotation but held against end-wise movement. The desired slight reciprocation for breaking up 30 grinding lines and transversing the work is imparted to the internal grinding wheel carriage unit by a suitable hydraulically actuated piston 38 movable in a cylinder 39 carried by the bed. Reversal of direction of actuation of the piston 35 is effected as by reversing lever 40 carried on the front of the grinder control box 41. This lever cooperates with the adjustable dogs or contacts 42 mounted on the forward face of the slide or carriage 33. By this construction a normal 40 constant reciprocation of amount pre-determined by the adjustment of the dogs is continuously applied to the grinding wheel unit during actuation of the machine except at such times as lever 40 is manually shifted to an intermediate or neutral 45 position.

50 Mounted on the ways 32 is the reciprocating table 43 coupled by a piston rod 44a, Fig. 23, with piston 160 movable in cylinder 159 carried by the bed. This piston is hydraulically operated in its cylinder for moving the table toward or from the grinding wheel unit.

55 The starting, stopping and reversing of the piston and thus of the table 43 is effected by suitable shifting of valve 158 shown in detail in Figure 12 operating in conjunction with certain timing and control mechanism as hereinafter described.

60 Movement of table 43 shifts the work supporting and controlling members carried thereby from disengaged or inoperative position, as shown in Figures 1 and 2 for example, to a position in which the grinding wheel 37 is operatively disposed within the bore or interior of a work piece 44.

65 It is desirable, in initiating the grinding as well as in withdrawing the parts from grinding relatively, to first have the grinding wheel disposed within the lateral bounds of the work and then subsequently feed the work as an entirety transversely of the machine into the grinding wheel 70 for the desired stock removal, rather than for the stock removal to be effected during the axial movement of the work and wheel into inter-engaged position and thus imposing an undue amount of work on one edge or portion of the 75 grinding wheel. To facilitate this manner of

engagement and relative feeding of grinding wheel, the work table 43 is preferably formed with the dove-tail guide 45 for the supplemental table or cross slide 46 which carries the work holding and grinding control mechanism.

5 The transverse or cross feed movement required for grinding of the work piece is normally slight and, as a consequence, may be attained through the use of a suitably actuated cam 47, Fig. 6, carried by the table 43 and engaging the 10 cam follower or roller 48; secured to the cross slide 46, said cam being rocked on its axis as will hereinafter appear in order to procure the crossfeed movement.

15 On the supplemental slide 46 is the swivel table 49, Figs. 2 and 5, having the worm rack 50 engageable with an adjusting screw 51, whereby the supplemental table may be set at different angles to the ways 31 and 32 for grinding tapered or conical surfaces on the work piece. A micrometer scale, as at 52, facilitates determination of the angle of adjustment of the swivel table. This table has the head 53 bearing clamp fingers 55, Fig. 4, to exteriorly engage and secure in position a ring or other hollow work piece 44 to be 20 operated upon by the grinding wheel 37. Power to rotate the work head or chuck at a slow rate of speed is applied to worm gear 57 on the spindle by worm 58, Fig. 5, on vertical shaft 59, which is journaled in the bearing bracket 53a.

25 The swivel table 49 is further provided with a depending annular flange 60 concentric to the bracket 53a in which is rotatably mounted the bushing 61 having a thrust bearing 62 backing up the bevel pinion 63 on the lower end of the 30 shaft 59. This bushing further carries a bearing 64 for sleeve 65 splined on drive shaft 66 and bearing a bevel pinion 67 intermeshed with pinion 63. Drive shaft 66 is primarily journaled in the bearing bracket 68 on the under 35 side of the table 43 and is provided with the stepped pulley 69 for suitable application of driving power thereto. By this construction it will be noted that the swivel table 49 may be rotated as desired without effecting the drive to the work 40 head spindle. At the same time, slide 46 may be given its desired back and forth movement, sleeve 60 operating in a suitable slot in the bed and sleeve 65 with its drive pinion 67 moving freely lengthwise of the splined portion of shaft 50 66. A suitable mechanism which may be employed for retracting the slide 46 and parts carried thereby, is shown in the present instance as comprising a cylinder 10 secured or formed in table 43 and containing a piston 71 having integral therewith a stud 72 bearing against the depending flange 60. This piston is intended to be suitably, hydraulically actuated or rearwardly urged continuously to press the slide toward the rear while permitting of free rotation of the swivel table. 55 The hydraulic pressure or volumetric urge in the cylinder 10 is of such nature as to yield and permit of forward movement of the slide under the influence of the actuating or cross feed cam 47, previously referred to, against roller 48. This 60 roller 48 is carried by the elongated nut 73, Fig. 6, in threaded engagement with screw 74 and slideable in recess 75 of the cross slide 46.

65 Cam 47 is secured to or integral with sleeve 76, Fig. 8, oscillately supported in carriage 43 by 70 pin 71. The sleeve has a depending arm 78 furcated as at 79, Fig. 9, to engage the block 80 swiveled on reciprocating piston 81, intermediate 75 movable in cylinder 82 formed in bracket 83 depending from the under side of table 43. A 75

suitable valve mechanism 85 controlled as by shift lever 86 coupled through linkage 87 and 88 with the solenoids 89 and 90 serves to control admission of actuating fluid to one end or the other of cylinder 82 and exhaust thereof from the opposite end and thus effect a hydro-electric control of the piston movement and consequently of the inward forcing or cross feed movement of the table 46 as a part of the automatic cycle of operations hereinafter described.

As mentioned, the forward or feeding movement effected by movement of the piston and cam is in opposition to the constant hydraulic pressure urge in cylinder 78 against piston 71 and rod 72 which gives automatic retraction or reverse movement of the supplemental table 46 and work head when cam 47 is oscillated into roller releasing position to procure retraction of the cross feed movement.

As the grinding wheel wears down during the operation on successive work pieces it is necessary to compensate for such wear so that all pieces may be ground to a standard internal diameter. This of course, may be effected manually but it is preferable that the compensation be cared for automatically. The mechanism for accomplishment of this is particularly illustrated in Figures 6, 7 and 8. Bracket member 83 which, as above noted, is secured to the under side of the table 43 has journaled therein the vertical shaft 91 having on its upper end a bevel gear 92 meshing with a similar gear 93 rotatable in the anti-friction bearings 94 supported by the table 43, said gear 93 having a sleeve portion 95 splined on the rear end 35 of screw 74 so that the screw may slide freely therethrough during reciprocating movement of cross slide 46. Shaft 91 has rotatably mounted on the lower portion thereof a disc 96 having integral therewith a spur gear 97 in permanent 40 mesh with gear 98 on a sleeve 99 which latter has a second gear 100 meshing with a rack 101, Fig. 8, on piston 81.

As the piston reciprocates the double gear 98 and 100 will be rotated, imparting a corresponding rotation to the disc 96 which is rotatable on a sleeve 102 splined to the lower end of shaft 91. The disc 96 has pivoted thereto a pawl 104 urged by spring 105 into engagement with ratchet 106 on sleeve 102 tending to rotate the ratchet and thus the shaft 91 in a counter-clockwise direction as the disc rotates in this manner. The pawl rides idly over the ratchet on movement of the disc in a reverse direction.

A knock-out screw 103 serves at a given point in the rotation of the disc to engage the outer end of the pawl moving said pawl away from the ratchet so that shaft 91, when the parts are in retracted position, may rotate freely as the screw 74 is manually adjusted. As the piston 81 moves rearward urging slide forward disc 96 will be rotated in a clock-wise direction. A greater or less amount of rotation will be given the disc depending upon the distance which the piston is to travel in urging the slide 46 forward before sufficient amount of stock has been removed from the work piece. During this movement pawl 104 will be shifted away from the knock-out screw 103 and will start to ride over the teeth of ratchet 106. If but a slight movement is given to the disc the pawl will contact with the ratchet tooth and ride along the face thereof without slipping down behind one of the teeth and will consequently move back to initial position without actuation of the ratchet.

On the other hand, if the grinding wheel is worn down to an extent requiring greater movement of the piston and cam 47 to effect proper infeed movement of the work head and its supporting table in the direction of the axis of the grinding wheel a correspondingly greater amount of rotation will be imparted through the double gear drive to the disc and pawl. The pawl will then drop back of a tooth on the ratchet and on return movement will rotatably shift the ratchet therewith, this rotation being transmitted through shaft 91 and gears 92 and 93 to the screw 74. The result is a rearward shifting of nut 73 and roller 48 with respect to table 43 at the same time that the table itself is moving rearwardly under the influence of piston 71 so that the table itself does not actually move as far in a retracted direction and less oscillation of cam 47 is necessary to impart a feeding stroke to the work in the next cycle in order that the reduced diameter grinding wheel may still grind the work to proper size.

In this manner an entirely mechanical, automatically operating mechanism is provided in which the movements of the cross slide control cam and associated parts are automatically effective to take up for wheel wear so that the machine can run indefinitely without the necessity for manual adjustment and yet the desired size of work pieces is attained and the movement of the table is procured by a non-adjustable or constant throw cam member.

The performance of a cyclic grinding operation by the machine on a series of similar work pieces is dependent on automatic control of the reciprocation of the grinding wheel, the movement of the work from loading or inoperative position to grinding position and relative feeding of the work and grinding wheel when in such relation to cause proper stock removal.

The cycle of these operations and the automatic control of the machine will be best understood by primary reference to Figure 22 in which the entire actuating and control system has been diagrammatically illustrated, considered in connection with the general actuation of wheel head and table above described and the several detailed views of particular mechanisms included in the present embodiment of the machine.

In Figure 22 continuous lines have been employed to indicate the several electrical circuits and broken or dash lines, the several hydraulic lines or conduits which, being of conventional form, have not been shown as an entirety in the drawings but only the coupling and controls thereof.

Use is preferably made of a suitable pump or fluid prime mover or impeller 110 and the system as illustrated is designed to use a fluid medium such as oil contained in tank 111 as its motive power. 112 designates the main pressure lines having leading therefrom branch 113 extending to the several table ways or other portions of the machine for lubrication thereof, a return 114 being provided to tank 111. In addition, pressure line 115 extends to the reversing valve 116 for selective connection to lines 117 and 118 from said valve 116 to the cylinder 38 which actuates the piston 38 for the grinding wheel slide. Valve 116 is controlled by engagement of dogs 42 with the valve operating lever 40 as indicated in Figure 1 to impart a constant reciprocating movement of prescribed amplitude to the grinding wheel as determined by the adjustment of the dogs 42. The electrical circuit

is connected as by switch 119, Fig. 1, with a suitable source of electrical energy, this circuit having been illustrated as comprising a pair of leads 120 and 121.

5 *The automatic cycle of operation*

With the parts in the position shown in Figure 1 of the drawings—that is to say, with the work head retracted, the cycle of operations will occur as follows.

10 An initial manual depression of a work loading arm 122, Figs. 2 and 3, carried by rock shaft 123, will cause the spring-pressed fingers 124 and 125 thereof, Fig. 20, which are in engagement with the work piece 44 in the lower end of chute 127, as shown in Fig. 3, to carry the work piece downwardly in an arcuate path through discharge slot 128 in the chute. Spring retaining finger 129 allows the carried work piece to move outwardly through the slot, while restraining the movement of the ensuing work pieces. As arm 122 moves downward, it carries the work piece into position for engagement by the work clamping fingers 55, which have been urged in open or work receiving position by resilient actuating means 126, Fig. 4. As the work reaches approximately this position, a cam 130 on arm 122, best shown in Fig. 18, will ride down the engaging cam surface 131, carried by member 53, allowing the arm and thus the work piece to move inwardly or to the left, thereby positioning the work piece between the fingers of the rotatable work receiving chuck. This movement of the arm 122 to the left is effected by spring 132.

15 During inward movement into operative position in the chuck, the work piece engages head 133, rotatably carried by the piston plunger rod 134, forcing the rod and its associated piston 135 toward the left as viewed in Figures 1 and 4. At 20 the same time, the movement of the arm 122 to the left causes it to engage lug 136, Fig. 3, of switch 137. The circuit 138, closed by this switch, includes a solenoid 139 coupled with valve 140, which latter, in response to energization of the solenoid 139, will be shifted to the right from the position indicated in Figure 22, thereby completing the hydraulic actuating circuit to the righthand end of cylinder 141, in which the chuck actuating piston 135 is movable.

25 This resultant movement of the piston 135 to the right forces the frusto-conical or wedge-shaped portion 145 of head 133 into locking engagement with the inwardly extending fingers 146 of the work clamps 55, securely clamping the work piece to be operated upon in position within its rotary chuck. Of course it is to be understood that the particular clamp mechanism illustrated is of purely conventional form and any desired work supporting and rotating member 30 may be utilized in this position, with its clamping effect controlled by movement of plunger 134. As the piston 135 and rod 134 are urged to the left in response to fluid under pressure, the lug 142 on the rod 134 will engage and close a switch 35 143 in the electrical control circuit 144. Electrical control circuit 144 includes solenoid 147, Fig. 22, for shifting valve 148 to the left, completing hydraulic pressure circuit 149 to the lefthand end of cylinder 150. This shifts piston 151 to 40 the right, as diagrammatically shown in Figure 22 and as shown in section in Figure 17. Piston 151 has a rack portion 153, meshing with pinion 154 on the rock shaft 123 on which the work loading arm 122 is mounted, so that as the piston 45 73 ton is shifted, as indicated, shaft 123 will be

given a counter-clockwise movement and the arm will be swung upward into the position indicated in Figure 3. This upward movement causes arm 122 to contact with switch 155 of control circuit 156, including the solenoid 157, which is thereupon energized to procure movement of the work head to bring the wheel and work into operative relation.

5 Energizing of solenoid 157, in response to movement of the arm 122, shifts valve 158 to the right, 10 as viewed in Figure 22, coupling pressure line 112 with the left hand end of the cylinder 159, which is carried by the bed 30 of the machine, thereby urging the piston 160 therein to the right, and, since the piston is coupled 15 by piston rod 44a with the table 43, procures movement of said table toward the right, Figure 1, to shift the work head and work carried thereby into operative position in which the work piece is in telescoping relation with the 20 grinding wheel 37. The work head may either be continuously rotated or may be stopped when in retracted position. The interruption of work head drive to bring the work head to rest for replacing of a finished work piece by an unground 25 work piece is preferably effected by control switch 161, Fig. 1, which is opened by engagement therewith of the table 43 when the latter is retracted to inoperative position and which is automatically closed to start rotation of the work as the table 30 moves to the right to operative position. Said switch operates a suitable clutch, not shown, for connecting and disconnecting the power supply to the chuck spindle. Movable with the table is dog 162, engageable with trip 163 coupled by link 35 164 with arm 165, Fig. 11, on rock shaft 166. As the table reaches its right limit of movement, it shifts arm 165 and thus the shaft 166. Referring now to Fig. 11, this shaft has a depending rock arm 167, formed with an enlarged aperture at 168 to span spindle 169 of the manual operating lever 170. The spindle 169 is coupled by arm 171 with pin 172 carried by the rock arm 167, for manual shifting of the latter, independently of its dog control. Rocking of shaft 166 in a clockwise direction, whether manually or automatically effected, moves cross arm 173, Fig. 10, integral with arm 167, in an arcuate path, the right-hand end thereof, as viewed in Figure 10, serving to tilt switch member 174 to depress switch plunger 175, see Fig. 14, closing the circuit through switch located at 176. This energizes electric control circuit 177, including solenoid 178, which in turn shifts valve 85, coupling hydraulic power circuit 112 with the right end 50 of cylinder 82 to shift piston 81 to the left. Movement of this piston, as hereinbefore described, through the medium of cam 47, causes a radial or cross feeding of the rotating work piece in 55 the direction of the oscillating grinding wheel for proper stock removal from the inner face thereof in the manner illustrated in Figure 3. At the same time, the mechanical connection of the shaft 166 through pin 172 to arm 180 oscillates rock shaft 181 to which the arm 180 is secured, and also oscillates the valve shifter arm 182, Fig. 11, thereby positively moving valve 158 60 to a neutral position, discontinuing the longitudinal movement of the work supporting table 43 toward the grinding wheel. The bed 30 is preferably additionally provided with a bracket 183 having a positive stop 184 thereon, Fig. 6, engageable with the dog 162 of the table definitely to limit the longitudinal movement of the work 65 70 75 75

supporting table 43 in the direction of the grinding medium.

The movement of piston 81 to rotate cam 47, thereby procuring the cross feed movement, will be continued until the work piece has been ground the prescribed amount. The mechanism illustrated for adjustably determining the amount of grinding in order that successive work pieces may be reduced to prescribed diameter, irrespective of wear on the grinding wheel, is particularly illustrated in connection with Figure 3 and comprises a casing 185, within which and the table 43 is journaled the supporting spindle 186 bearing the guide 187 for the adjustable sizing head device 188. This device includes a depending pivoted arm 189, having at its lower end a contact 190 normally disposed immediately adjacent the work piece for engagement by the grinding wheel during its reciprocating movement. The contact point 190 is set in definite relation to the axis of rotation of the work piece and moves with said work piece and its supporting table in the direction of the grinding wheel. As the grinding progresses, the wheel grinds deeper and deeper into the work as a result of the cross feed movement, until the periphery of said wheel engages contact 190, producing an oscillation of lever 189. This lever is in the control circuit 191 of the machine, the circuit being completed through contact 192 on oscillation of the lever and being temporarily held in closed position as by the electric magnet 193 in series therewith. Completion of the control circuit 191, which occurs when the work piece is completely ground to the desired size, energizes solenoid 90, reversing valve 85 to admit fluid under pressure to the opposite side of the piston 81, causing its reversal of movement in the opposite direction. By this reversal of the movement of the piston 81, cross feed slide 46 is forced into retracted position, by the effect of the constant return pressure in cylinder 70, to withdraw the work piece radially from the grinding wheel. Branching from circuit 191 is a second circuit 196, also completed through the sizing device mechanism including lever 189. This circuit actuates solenoid 197 simultaneously with the solenoid 90 to reverse valve 158, so that, as the work is radially retracted or moved back with respect to the grinding wheel, as above stated, the entire work table is retracted to procure axial separation of the grinding wheel and work piece. This movement continues until dog 198 on the table 43 engages trip 163, rocking said trip and thus the table control valve 158 in a reverse direction to shift this valve to neutral. This oscillation of the trip 163 also operates switch 199, Fig. 10, of electrical circuit 200, including solenoid 201, which reverses valve 140, reversing the flow of actuating fluid to cylinder 141, moving piston 135 and rod 134 to the right. This movement first causes clamp head 133 to release locking retention of the clamped fingers 55, so that the work is loosely held thereby, and continued movement of the rod positively ejects the completed work piece, which may then be discharged as through trough 202. As the work piece is ejected, lug 142 on rod 134 operates to close switch 203 of control circuit 204, energizing solenoid 205 to shift valve 148, thereby actuating piston 151 to oscillate the feed arm 122, as initially described, carrying down an unground work piece into alignment with and into the work head, when the clamping, grinding and ejection will again be repeated in properly related sequence. It will be noted that the actual actua-

tion of valve 148 is effected by linkage 206 and 207, Fig. 10, coupling the solenoids 147 and 205 with arm 208 on shaft 213 connected by shifter fork 210 with the valve 148 (see Figures 10, 11 and 13). Shaft 213 is further provided with an extension 212 adapted, when the shaft is oscillated, to kick over arm 211 on control sleeve 209 for the chuck actuating valve 140, shifting this valve to a neutral position so that the chuck actuating rod 134 may yield on pressure of the work thereagainst and will move back from ejecting position to allow the work to be properly seated within the clamp head under the influence of spring 132. It will be noted that the connection between the extension 212 and arm 211 has a lost motion so that there is no interference between the subsequent continued movement of valve 140 from the neutral position to a position for admitting fluid under pressure into the right-hand end of cylinder 141, for positively securing the work piece in position for grinding.

Mention has been made of the fact that the sizing device overlies the work in position for engagement with the operative face of the grinding wheel. To facilitate automatic movement of the sizing device out of said relation for ejection of a completed work piece and insertion of a fresh one, the support 186 is preferably provided with a pinion 214, Fig. 3, meshing with a slideable rack bar 215 adapted to contact with the adjustable stop 216, Fig. 2, as the table is retracted. This stop will then impart movement to the rack bar, oscillating support 186 and the sizing device out of alignment with the work piece. Suitable means, such as spring 217, serves to urge the sizing device into operative position as the work table is moved inward, and interlocking abutments 218 and 219 on the support 186 and casing 185 respectively serve to limit the oscillatory movement of the sizing fixture in the direction of the work head.

Further controlling complete automatic operation of the machine, the coolant line 220 is preferably provided with a spring closed valve 221 having a projecting stem 222 engageable by abutment 223 on the table, so that, as the table advances the work to grinding position, this abutment will automatically open the valve for supply of coolant at the grinding position, while on retraction of the parts, the flow of coolant will be automatically shut off.

Particular attention is invited to the fact that the various control valves for the machine are preferably located in a general control box unit 224 disposed on the front of the bed and extending thereinto, the actuating members or rock shafts 181 and 209 being nested, one within the other, whereby the one serves as a support for the other, and the several control solenoids provide a juxtaposition grouping of the electric control mechanism as an entirety.

Particular attention is also invited to the structure of the control switch devices 176, 198 and 155, the first two respectively operated by opposite oscillations of arm 173 and the third device 65 by arm 122. One of these is shown in detail in Figure 14 and it will be noted comprises the oscillatable actuating member 174 freely riding away from the switch and depressing stabilizing plunger 225 as the arm moves in one direction 70 while operative to depress the switch plunger and temporarily close the actuating circuit as it moves past the lug 226 in the reverse direction.

From the foregoing description, considered in connection with the drawings, the construction 75

and advantages of the present machine should be readily understood. It will be noted that there has been provided a mechanism in which the high speed grinding wheel is given a constant reciprocation in its operating position and, due to absence of other movements, is supported with maximum rigidity. Additionally, it will be noted that the work holding mechanism has been illustrated as mounted both for movement into operative position or with its work holding portion telescoping with the grinding wheel, both of prescribed amplitude of reciprocation and in which the work supporting unit is also given a radial or cross feeding movement as respects the grinding wheel for proper presentation of the work to the operative surface of the wheel. It is to be understood, however, that while this is illustrated as the preferred embodiment in the present instance, and an automatic mechanism has been shown for accomplishing this feeding, that a corresponding mechanism might be utilized for imparting the radial or feeding movement, to the grinding wheel in place of the work supporting unit, with the adoption of control mechanism for the complete cycle such as hereinbefore described, without exceeding the purview of the broad expression of the present invention.

It will further be noted that there has been provided a completely automatic mechanism, in which the entire attention of the operator may be devoted to supplying work pieces to the suitable feed or hopper mechanism and in which the work pieces are successively transferred from the hopper mechanism to the work supporting unit, shown as a chuck. The work piece is then brought in overlying relation to the grinding wheel, and relative feed imparted to the parts until a prescribed amount of grinding has been performed, which grinding action is automatically measured and determined. After the work piece has been reduced the prescribed amount, the mechanism automatically releases the cycle of operation to cause a relative axial and radial separation of work piece and grinding member, after which the completed work piece is automatically ejected or discharged and a new work piece substituted.

Attention is further invited to the fact that in the present improved automatic mechanism, the preferred embodiment of the cycle controls of operation has been shown as comprising a series of hydraulically actuated pistons for axially effecting the several power movements combined with mechano-electric control mechanism for regulating the effective position of the various valve hydraulic units. It is again to be understood, however, that so far as the broad invention and general cycle of operation is concerned, the movements could be effected by screw feed or other convenient devices combined with either electrical controls, mechanical clutches or the like, for successively determining the actuation of the parts so long as the prescribed cycle of operations is attained.

65 We claim:

1. A grinding machine comprising a bed, a grinding wheel supported thereby for interior engagement with a work piece, means for rotatably supporting a work piece, means for axially advancing the work piece in the direction of the grinding wheel and means for transversely feeding the work piece in opposition to the operative surface of the grinding wheel, a sizing determinator for engagement with the operative surface of the wheel, and means controlled by the size

determinator for laterally and axially withdrawing the work when the same has been ground to predetermined size.

2. A grinding machine comprising a bed, a grinding wheel supported thereby for interior engagement with a work piece, means for rotatably supporting a work piece, means for axially advancing the work piece in the direction of the grinding wheel and means for transversely feeding the work piece in opposition to the operative surface of the grinding wheel, a sizing determinator for engagement with the surface of the wheel, means controlled by the size determinator for laterally and axially withdrawing the work when the same has been ground to predetermined size, and means actuated by withdrawal of the work piece for automatic ejection thereof.

3. A grinding machine including a bed, a grinding wheel supported thereby for reciprocation relative thereto, a work holding unit supported by the bed, means for shifting the work holding unit in direction of reciprocation of the grinding wheel for presentation of a work piece thereto, additional means for shifting the work holder in a direction at right angles to the direction of reciprocation of the grinding wheel for feeding a work piece held by the unit into operative engagement with the grinding wheel, a grinding determinator for engagement with the surface of the grinding wheel, means controlled by movement of the determinator for reversing the feeding movement of the unit, and additional mechanism rendered operative by said reversal for retracting the unit with respect to the grinding wheel.

4. A grinding machine including a bed, a grinding wheel slidably supported by the bed, means for imparting a constant reciprocation of prescribed amplitude to the grinding wheel as respects the bed, a work holder unit supported by the bed having a work holding portion movable into and out of alignment with the path of reciprocation of the grinding wheel, means for shifting the work holding unit on the bed into and out of said operative relation with the grinding wheel, means for automatically imparting a transverse feeding movement to the work holding unit when in alignment with the grinding wheel to shift a work piece into operative engagement with said wheel, a gaging member engageable with the grinding wheel for determining its operative relation to the work, means controlled by the gaging member for reversing the feed when the article has been ground to a prescribed size, and means effective on said reversal of movement for removing the work piece from the work holder.

5. A machine for grinding the interior of hollow work pieces comprising a bed, a grinding wheel carried by the bed, a work holder unit movably mounted on the bed, means for shifting the work holder unit in an axial direction as respects the grinding wheel for presentation of a work piece in operative relation thereto, dog control means for limiting said movement of the work controlling unit, means operative on limitation of said movement of the work holding unit for initiating a relative feeding of the work and the grinding wheel, a gaging member in predetermined relation to the work holding unit for determining the grinding action on the work piece, means actuated by said gage for reversing the feed when the prescribed grinding has been performed, means actuated by said reversal for moving the work holding unit axially away from

the grinding wheel, an ejector, means for operating the ejector upon said withdrawal and automatic means for effecting reverse shifting of the work holding unit into operative relation with the grinding wheel.

5 6. In a machine of the character described, the combination with a bed, of a grinding wheel supported thereby, a work supporting unit carried by the bed, means for imparting relative movement to said members on the bed in a direction axially of the grinding wheel, mechanically operable means for limiting the relative approach and retraction of the parts, electrically controlled mechanisms for imparting a relative feeding and 10 retraction to the parts in a direction radially of the grinding wheel when the parts are in their proximate position, and additional electrically controlled means for ejecting a work piece when the parts are in their relatively retracted position.

15 7. In a machine of the character described the combination with a bed, of a grinding wheel supported thereby, a work supporting unit mounted on the bed including a traversing table and a carriage movable on the table at right angles to the 20 traverse thereof for feeding purposes, a control cylinder and hydraulically actuatable piston for imparting traversing movement to the table, a second control cylinder and hydraulically actuated piston for effecting cross feed of the carriage, 25 control valves for said cylinders, solenoid members for shifting the valves to various effective 30 positions, control circuits coupled with the solenoids, means for successively completing said control circuits to actuate the valves in predetermined sequence, an ejector member for removal 35 of a finished work piece, a control cylinder and hydraulically actuated piston for effecting desired movements of the ejector, a control valve for said cylinder, electric circuits including solenoids for effecting selected movements of the 40 valve, and inter-related means for completing said circuits in predetermined relation to the completion of the unit shifting circuits to eject a completed work piece at a desired period in 45 relation to the movement of the table and carriage.

8. A grinding machine of the character described, including a bed or support, a first slide mounted thereon for reciprocation relative thereto, a grinding wheel mounted thereon, means including a reversible hydraulic motor for effecting reciprocations of the slide on the bed, a second slide movable on the bed in a direction parallel to that of the first slide, hydraulic means for effecting movement of said slide, a work support 50 mounted on said second slide for movement therewith and relative thereto in a direction transverse to the direction of movement of the slide, and control means for alternatively effecting the movement of the second slide and of the work support with respect to its slide.

9. A grinding machine of the character described, including a bed or support, a first slide mounted thereon for reciprocation relative thereto, a grinding wheel mounted thereon, means including a reversible hydraulic motor for effecting reciprocations of the slide on the bed, a second slide movable on the bed in a direction parallel to that of the first slide, hydraulic means for effecting movement of said slide, a work support 55 mounted on said second slide for movement therewith and relative thereto in a direction transverse to the direction of movement of the slide, control means for alternatively effecting the movement of the second slide and of the work support with respect to its slide.

support with respect to its slide, and means for automatically actuating the control means in predetermined sequence.

10. An internal grinding machine including a bed or support, a first slide mounted for reciprocation on the bed, a grinding wheel on said slide, hydraulic means for effecting individual slide including power operated reversing means, a work support, slides intervening the work support and bed and operable to shift a work piece 10 in the support into position for engagement by the grinding wheel and in a transverse direction for effecting a feeding movement of the work with respect to the grinding wheel, independent hydraulically actuated means for effecting said 15 positioning and feeding movements of the work support, and control means for simultaneously discontinuing movement of the work support in one direction and initiating its movement in an angularly related direction.

20 11. An internal grinding machine including a bed or support, a first slide mounted for reciprocation on the bed, a grinding wheel carried by said slide, hydraulic means for effecting said reciprocation including power operated reversing 25 means, a work support, slides intervening the work support and bed and operable to shift a work piece in the support into position for engagement by the grinding wheel and in a transverse direction for effecting a feeding movement 30 of the work with respect to the grinding wheel, independent hydraulically actuated means for effecting said positioning and feeding movements of the work support, control means for simultaneously discontinuing movement of the work 35 support in one direction and initiating its movement in an angularly related direction for effecting desired stock removal from the work, and means for simultaneously effecting a radial and axial retracting movement of the work at the 40 completion of the grinding operation.

12. A grinding machine of the character described, including a bed or support, a first slide mounted thereon for reciprocation relative thereto, means including a reversible hydraulic motor 45 for effecting reciprocations of the slide on the bed, a second slide movable on the bed in a direction parallel to that of the first slide, hydraulic means for effecting movement of said slide, a work support mounted on said second slide for 50 movement therewith and relative thereto in a direction transverse to the direction of movement of the slide, control means for alternatively effecting the movement of the second slide and of the work support with respect to its slide, means 55 for automatically actuating the control means in predetermined sequence, a work feeding member for supplying a work piece to the work support in grinding position, and means for actuating the feeding device prior to movement of the work 60 support into grinding position.

13. A grinding machine of the character described, including a bed or support, a first slide mounted thereon for reciprocation relative thereto, means including a reversible hydraulic motor 65 for effecting reciprocations of the slide on the bed, a second slide movable on the bed in a direction parallel to that of the first slide, hydraulic means for effecting movement of said slide, a work support mounted on said second slide for 70 movement therewith and relative thereto in a direction transverse to the direction of movement of the slide, control means for alternatively effecting the movement of the second slide and of the work support with respect to its

- slide, means for automatically actuating the control means in predetermined sequence, a work feeding member for supplying a work piece to the work support in grinding position, means for actuating the feeding device prior to movement of the work support into grinding position, and means for discharging a completed work piece when the work support is shifted into non-grinding position.
14. In a machine of the character described, the combination with a grinding wheel and means for supporting a work piece in opposition thereto, of an hydraulic control mechanism for determining the effective position of the work support including an hydraulic member exerting a continuous urge of the work support into retracted position and an independent hydraulic mechanism for imparting a prescribed positive feeding movement to the work support in the direction of the grinding wheel and in opposition to the urge of the first hydraulically actuated work support shifting member.
15. In a machine of the character described, the combination with a grinding wheel and means for supporting a work piece in opposition thereto, of an hydraulic control mechanism for determining the effective position of the work support including an hydraulic member exerting a continuous urge of the work support into retracted position, an independent hydraulic mechanism for imparting a prescribed positive feeding movement to the work support in the direction of the grinding wheel and in opposition to the urge of the first hydraulically actuated work support shifting member, and power operated means for rendering the hydraulic feed mechanism effective.
16. In a machine of the character described, the combination with a grinding wheel and means for supporting a work piece in opposition thereto, of an hydraulic control mechanism for determining the effective position of the work support including an hydraulic member exerting a continuous urge of the work support into retracted position, an independent hydraulic mechanism for imparting a prescribed positive feeding movement to the work support in the direction of the grinding wheel and in opposition to the urge of the first hydraulically actuated work support shifting member, power operated means for rendering the hydraulic feed mechanism effective, and additional control mechanism including a work size determinator effective to reverse the characteristic of the action of said feed effecting means.
17. An internal grinder including a bed, a grinding wheel supported thereon, a work support movable in a direction parallel with the axis of rotation of the grinding wheel for presentation of work to, and retraction thereof from, grinding position, a size determinator movable with the work support and movable relative to the work support into and out of overlying relation to a work piece in operative position thereto, means for automatically ejecting a work piece on retraction of the work support, and additional means for automatically shifting the size determinator out of overlying relation to the work prior to the work piece ejection.
18. A grinding machine of the nature described, including a grinding wheel and work supporting mechanism for presentation of the work to the grinding wheel, including a pair of slides movable in angularly related directions and respectively operable for presenta-
- tion of work in the zone of operations of the grinding wheel and for effecting a feeding movement of the work as respects the grinding wheel, hydraulic means for effecting individual slide movements, a remote master control unit including valve mechanism for determining the hydraulic actuation of the individual slides, electro-mechanical control mechanism in the master unit for selectively shifting the valve mechanisms to determine the actuation of the slides, hydraulically actuatable work clamping mechanism carried by the slides, and additional valve mechanism in the master control unit for determining the action of the work clamping and releasing mechanism.
19. In a machine of the nature described, the combination with a bed of a work support mechanism including a first slide movable on the bed and a second slide mounted on the first for movement therewith and relative thereto, independent hydraulically actuatable mechanisms for effecting the movement of each of the slides, individual control valves for the mechanisms, a trip operable valve shifter actuatable by the first slide for discontinuing movement thereof, and means operated by said trip mechanism on movement in one direction for shifting the control valve of the other slide to initiate movement of said latter slide.
20. In a machine of the nature described, the combination with a bed of a work support mechanism including a first slide movable on the bed and a second slide mounted on the first for movement therewith and relative thereto, independent hydraulically actuatable mechanisms for effecting the movement of each of the slides, individual control valves for the mechanisms, a trip operable valve shifter actuatable by the first slide for discontinuing movement thereof, means operated by said trip mechanism on movement in one direction for shifting the control valve of the other slide to initiate movement of said latter slide, a work feeding mechanism for supplying work pieces in operative position on the work support, and means actuated by movement of the trip mechanism in the opposite direction for initiating actuation of the work feed mechanism.
21. In a machine of the character described, the combination with a bed of a work support slide mounted thereon for movement relative thereto, hydraulic means for effecting translation of the slide on the table including a reversing valve, control means including a trip operable member for actuating the valve to interrupt the hydraulic urge of the slide, a stop member carried by the machine adjacent said control means, and dog mechanism on the slide positioned sequentially to engage said control means and the stop to discontinue the urge of the slide and positively limit the movement thereof.
22. An internal grinding machine including a bed, an internal grinding wheel spindle and a work support mounted on the bed in axially opposed position, means for effecting a translation of one of said parts in a direction toward and from the other to project the grinding wheel spindle within the work support for operation on a work piece held thereby, hydraulic operating means including a piston and cylinder for effecting relative radial feeding movement of the parts when in grinding relation, and control means for simultaneously discontinuing the relative axial movement of the parts and initiating operation of the hydraulic feed mechanism for effecting a grinding of the work piece.

23. An internal grinding machine including a bed, a grinding wheel mounted thereon, hydraulic means for imparting a constant limited reciprocation to the grinding wheel on the bed, mechanical means for controlling said reciprocation, a work holding unit movable longitudinally of the bed for presentation of work in operative relation to the grinding wheel and movable transversely of the bed to feed the work against the grinding wheel, hydraulically actuatable means for imparting said longitudinal and transverse feeding movements to the work supporting unit, means on the unit for supporting a work piece, and means for varying the position of said supporting means relative to the unit to vary the presentation of the work to the grinding wheel for a given movement of the unit. 10
24. A grinding machine comprising a base, a grinding member, a work-supporting member, means for procuring an advance of said members toward each other to position the grinding member within a workpiece in the work-supporting member, means for procuring a crossfeed movement between the members, a gage having a feeler engageable with the operative surface of the grinding member, and means controlled by said gage for procuring a retraction of the crossfeed movement and an axial withdrawal of the grinding member from within the bore of the workpiece. 20
25. A grinding machine comprising a base, a grinding member, a work-supporting member, means for procuring an advance of said members toward each other to position the grinding member within a workpiece in the work-supporting member, means for procuring a crossfeed movement between the members, a gage having a feeler engageable with the operative surface of the grinding member, means controlled by said gage for procuring a retraction of the crossfeed movement and an axial withdrawal of the grinding member from within the bore of the workpiece, and automatically actuated means for ejecting the workpiece from the work-supporting member. 30
26. A grinding machine comprising a base, a grinding member, a work-supporting member, means for procuring an advance of said members toward each other to position the grinding member within a workpiece in the work-supporting member, means for procuring a crossfeed movement between the members, a gage having a feeler engageable with the operative surface of the grinding member, means controlled by said gage for procuring a retraction of the crossfeed movement and an axial withdrawal of the grinding member from within the bore of the workpiece, and means responsive to the relative withdrawal of the grinding member from within the bore of the workpiece for procuring a discharge of the workpiece from within the work-supporting member. 5
27. In an internal grinding machine the combination with a bed, of a grinding wheel carried thereby, a work-supporting unit on the bed, actuating means for shifting the unit on the bed in a direction axially of the grinding wheel, mechanical means operable by movement of the unit in said direction for discontinuing said movement, means for effecting a feeding movement of the unit and grinding wheel one with respect to the other for grinding of a workpiece and a subsequent withdrawal of the unit, an ejector for removing a workpiece from operative position within the unit and means actuatable on movement of the ejector for initiating movement of the unit toward the grinding wheel. 10
28. A grinding machine of the character described including a bed, a grinding wheel supported by the bed, a work-supporting unit mounted for relative movement on the bed in axial and radial direction, means for imparting said movements, and cyclic control mechanism for the several movements including mechanical means for checking the axial movement of the unit in the direction of the grinding wheel, an electric control actuatable by said mechanical means for initiating relative radial or feeding movement of the work unit and grinding wheel, additional electrical means for reversing the feeding movement and initiating an axial retraction of the unit, mechanical means for limiting said axial retraction, an ejector, electrical control means operable by said mechanical limiting means for effecting actuation of the ejector, and electrical controls actuatable by movement of the ejector for reversing the direction of movement of the ejector and initiating movement of the work-supporting unit in the direction of the grinding wheel. 15
29. A grinding machine comprising a base, a grinding member, a work-supporting member, means for procuring an advance of said members toward each other to position the grinding member within a workpiece in the work-supporting member, means for procuring a crossfeed movement between the members, a gage having a feeler engageable with the operative surface of the grinding member, means controlled by said gage for procuring a retraction of the crossfeed movement and an axial withdrawal of the grinding member from within the bore of the workpiece, and means responsive to the relative withdrawal of the grinding member from within the bore of the workpiece for procuring a discharge of the workpiece from within the work-supporting member. 20
30. A grinding machine of the character described including a bed, a grinding wheel supported by the bed, a work-supporting unit mounted for relative movement on the bed in axial and radial direction, means for imparting said movements, and cyclic control mechanism for the several movements including mechanical means for checking the axial movement of the unit in the direction of the grinding wheel, an electric control actuatable by said mechanical means for initiating relative radial or feeding movement of the work unit and grinding wheel, additional electrical means for reversing the feeding movement and initiating an axial retraction of the unit, mechanical means for limiting said axial retraction, an ejector, electrical control means operable by said mechanical limiting means for effecting actuation of the ejector, and electrical controls actuatable by movement of the ejector for reversing the direction of movement of the ejector and initiating movement of the work-supporting unit in the direction of the grinding wheel. 25
31. A grinding machine comprising a base, a grinding member, a work-supporting member, means for procuring an advance of said members toward each other to position the grinding member within a workpiece in the work-supporting member, means for procuring a crossfeed movement between the members, a gage having a feeler engageable with the operative surface of the grinding member, means controlled by said gage for procuring a retraction of the crossfeed movement and an axial withdrawal of the grinding member from within the bore of the workpiece, and means responsive to the relative withdrawal of the grinding member from within the bore of the workpiece for procuring a discharge of the workpiece from within the work-supporting member. 30
32. A grinding machine comprising a base, a grinding member, a work-supporting member, means for procuring an advance of said members toward each other to position the grinding member within a workpiece in the work-supporting member, means for procuring a crossfeed movement between the members, a gage having a feeler engageable with the operative surface of the grinding member, means controlled by said gage for procuring a retraction of the crossfeed movement and an axial withdrawal of the grinding member from within the bore of the workpiece, and means responsive to the relative withdrawal of the grinding member from within the bore of the workpiece for procuring a discharge of the workpiece from within the work-supporting member. 35
33. A grinding machine comprising a base, a grinding member, a work-supporting member, means for procuring an advance of said members toward each other to position the grinding member within a workpiece in the work-supporting member, means for procuring a crossfeed movement between the members, a gage having a feeler engageable with the operative surface of the grinding member, means controlled by said gage for procuring a retraction of the crossfeed movement and an axial withdrawal of the grinding member from within the bore of the workpiece, and means responsive to the relative withdrawal of the grinding member from within the bore of the workpiece for procuring a discharge of the workpiece from within the work-supporting member. 40
34. A grinding machine comprising a base, a grinding member, a work-supporting member, means for procuring an advance of said members toward each other to position the grinding member within a workpiece in the work-supporting member, means for procuring a crossfeed movement between the members, a gage having a feeler engageable with the operative surface of the grinding member, means controlled by said gage for procuring a retraction of the crossfeed movement and an axial withdrawal of the grinding member from within the bore of the workpiece, and means responsive to the relative withdrawal of the grinding member from within the bore of the workpiece for procuring a discharge of the workpiece from within the work-supporting member. 45

CERTIFICATE OF CORRECTION.

Patent No. 2,032,268.

February 25, 1936.

SOL EINSTEIN, ET AL.

It is hereby certified that error appears in the printed specification of the above numbered patent requiring correction as follows: Page 7, second column, line 7, claim 10, for "individul slide" read said reciprocation; and that the said Letters Patent should be read with this correction therein that the same may conform to the record of the case in the Patent Office.

Signed and sealed this 14th day of April, A. D. 1936.

Leslie Frazer

Acting Commissioner of Patents.
